(57) **CLAIM**

The ornamental design for a flow-through LED carrier for luminaire, as shown and described.

DESCRIPTION

FIG. 1 is a perspective view of a luminaire incorporating a flow-through LED carrier in accordance with the invention; FIG. 2 is a perspective view of a flow-through LED carrier for luminaire in accordance with the invention;

FIG. 3 is a front elevational view of the carrier of FIG. 2;

FIG. 4 is a rear elevational view of the carrier of FIG. 2;

FIG. 5 is a left side elevational view of the carrier of FIG. 2;

FIG. 6 is a right side elevational view of the carrier of FIG. 2;

FIG. 7 is a top plan view of the carrier of FIG. 2; and,

FIG. 8 is a bottom plan view of the carrier of FIG. 2.

The surface character of the interior portions of the carrier, seen in FIGS. 2, 7 and 8, is consistent throughout the full length of thereof. The broken lines are directed to environment, are for illustrative purposes only, and form no part of the claimed design or any embodiment thereof.
